UNITED STATES PATENT OFFICE

JESSE E. WAGGONER, OF HICKORY, NORTH CAROLINA

STEP PLATE FOR THE RUNNING BOARDS OF VEHICLES

Application filed May 19, 1928. Serial No. 278,991.

The present invention relates to step plates for the running board of an automobile or other vehicle and has for its principal object to provide a rotatable mounting for the 5 step plate whereby to permit the foot of a person to turn the step plate as the weight of the person is placed thereon and thus prevent the twisting of the foot upon the running board, as is customary in the present 10 practice while the body of the person is being turned while entering the vehicle.

A further object of the invention is to eliminate wear upon the upper surface of the running board by the foot of the person 15 while entering or leaving the vehicle.

A still further object is to provide a device of this character of a simple and practical construction, which is efficient and reliable in performance, neat and attractive in 20 appearance, relatively inexpensive to manufacture and which may be quickly installed in position without making any changes in the construction of the vehicle and otherwise well adapted to the purpose for which the 25 same is intended.

Other objects and advantages reside in the special construction, combination and arrangement of the various elements forming the invention as more fully hereinafter described and claimed, reference being had to the accompanying drawings forming part hereof, wherein like numerals refer to like parts throughout, and in which,

In the drawings:

35 Figure 1 is a top plan view and Figure 2 is a transverse vertical sectional view taken along a line 2—2 of Figure 1.

Referring to the drawing in detail, wherein for the purpose of illustration, I have 40 disclosed a preferred embodiment of the invention, the numeral 5 represents an attaching plate of a substantially rectangular formation and having attaching holes 6 formed adjacent the corner thereof whereby 45 to receive attaching screws 7 or the like for securing the plate upon the upper surface of running board.

The center of the plate is provided with a threaded opening within which a screw 8 50 is threadedly inserted, the upper end of the

screw, provided with the head 9 projecting substantially above the plate and is extended through a central opening formed in the step plate 10.

The bore of the opening in the step plate 55 is smooth so as to permit the free rotary movement thereof upon the screw and the head of the screw 9 is countersunk in the upper surface of the step plate as clearly shown in Figure 2 of the drawings. The 60 upper surface of the attaching plate 5 and the under surface of the step plate 10 are each provided with an annular disposed groove 11 disposed in superimposed relation with respect to each other and within which 65 is seated a plurality of ball bearings 12.

Bearings of sufficient dimension are provided for slightly placing the plates apart as clearly illustrated in Figure 2 of the drawings. The upper surface of the step 70 plate 10 is provided with a series of concentric grooves 13 whereby to prevent the slipping of the foot upon the step plate when the same is placed thereon.

It will be apparent from the foregoing 75 that upon fixedly attaching the attaching plate 5 to the upper surface of the running board and mounting the step plate 10 in position thereon that the same will be free to rotate upon the placing of the foot thereon and turning the foot in a customary manner while the person enters or leaves the vehicle. The step plate thus protects the running board from wear and at the same time prevents the twisting of the foot of the 80 person in an unnatural manner while stepping into or out of the machine.

The area of the attaching plate 5 is sufficient to completely underlie the step-plate 10 and at the outer edge on the under side 90 of the step plate is formed a downwardly depending flange 14 adapted to prevent the entrance of dirt under the step plate to interfere with the free rotation of the same 95 on the ball bearings.

The attaching plate may also be provided with water drain openings 15 to prevent dilution of the lubricant provided in the grooves 11 for the bearings and the attaching plate is also supported slightly above the 100

running board by spacing washers 16 to enable the water to drain freely from the plate.

It is obvious that my invention is susceptible to various changes and modifications in construction without departing from the spirit of the invention or the scope of the appended claim, and I accordingly claim all such forms of the device to which I am entitled.

Having thus described my invention, what I claim as new is:

A step plate of the character described comprising a flat polygonal plate having openings in its corner portions for the passage of securing elements, a pivot pin threadedly anchored in the central portion of the plate and extending outwardly therefrom and having a tapered slotted head on its upper end, a flat metallic disc mounted for rotation on the pin in spaced relation to the plate and having a countersunk bore for the reception of said pin and the tapered head, said disc of less diameter than the plate, the opposed faces of the disc and the plate being provided with complementary annular concentric grooves, anti-friction balls disposed in the grooves and a depending marginal flange on the disc for rotatable engagement with the plate.

In testimony whereof I affix my signature.

JESSE E. WAGGONER.
